UNITED STATES PATENT OFFICE.

ALFRED C. GILBERT, OF NEW HAVEN, CONNECTICUT, ASSIGNOR TO THE A. C. GILBERT COMPANY, OF NEW HAVEN, CONNECTICUT, A CORPORATION OF CONNECTICUT.

TOY VEHICLE.

Application filed July 14, 1919. Serial No. 310,561.

To all whom it may concern:

Be it known that I, ALFRED C. GILBERT, a citizen of the United States, residing in New Haven, county of New Haven, State 5 of Connecticut, have invented certain new and useful Improvements in Toy Vehicles, of which the following is a full, clear, and exact description.

This invention relates to toys, and more 10 particularly to toys of that class termed construction toys, designed to be assembled to produce various different toy devices. The present invention pertains more particularly to the assemblage of these construction parts to produce a knockdown toy 15 vehicle provided with a front and rear axle.

In my application, Serial No. 292,877, filed April 26, 1919, I have described and claimed a toy of this general type in which 20 the parts are assembled to produce a toy vehicle of the cart type provided with a single axle. The present application relates to the assemblage of these toy construction parts to produce, as above stated, a vehicle 25 provided with front and rear axles.

One of the objects of the present invention is to furnish toy construction parts which may be secured to a body member in various positions to produce a knockdown 30 toy vehicle provided with a front and rear axle having wheels mounted thereupon. Certain features of the invention, however, are not necessarily limited to use in wheeled toys, since they are applicable with equal advantage 35 to structures having runners, such as slides.

Another object of my invention is to provide toy construction parts of the type above indicated, which may be readily assembled 40 to form a pivotal mounting for pivotally securing the front axle of the toy vehicle to its body member.

A further object of my invention is to provide novel means for securing a draft 45 tongue to the front axle of a toy vehicle.

To these and other ends the invention consists in the novel features and combinations of parts to be hereinafter described and claimed.

50 In the accompanying drawing:

Fig. 1 is a perspective view of an express wagon embodying my invention.

Fig. 2 is an enlarged front view of Fig. 1, the tongue of the express wagon being 55 removed.

Figs. 3 and 4 are plan and side views respectively of a portion of the draft tongue and means for securing the same to the express wagon.

Fig. 5 is an enlarged sectional view taken 60 on the line 5—5 of Fig. 2; and

Fig. 6 is a plan view of a board or body member shown removed from the express wagon.

In the accompanying drawing, I have 65 illustrated the elements of my invention as assembled to construct a child's express wagon having a rectangular boxlike body, but it will be apparent that these elements may be assembled to form the running gear 70 for various types of wagons without departing from the spirit of my invention.

I have designated by the numeral 10 a board or body member upon the upper face of which is preferably secured a rectangular 75 frame designated in its entirety by the numeral 11 and consisting of side and end members secured together, while this frame 11 is secured to the body member 10 to form a boxlike body for my express wagon, however, the frame 11 forms no part of my invention herein described. The board or body member 10 preferably has a number of bolt holes 12 formed therethrough is spaced relation, and to the lower face of the member 80 10 are secured the front and rear brackets 13 by means of bolts 14 which pass through the bolt holes 12 and through the inwardly directed ears 15 of the brackets 13. By providing a plurality of bolt holes through the 85 body member, the brackets 13 may be secured to the same in various positions. Each of the inwardly directed ears 15 is provided with a drill-hole 16 (see Fig. 5) adapted to receive one of the bolts 14. My toy vehicle 90 is provided with a rear axle 17 and a front axle 18, upon the opposite ends of which are mounted wheels 19 of any desired construction and which may be secured to the axles in any desired manner, but in the drawing, 100 I have disclosed these wheels as retained in place upon the axles by cotter pins 20. The brackets 13 are provided to connect the front and rear axles to the body of my toy vehicle, and the rear axle 17 is rigidly but removably secured to the rear brackets 13 by means of the U-shaped clips 21, the spaced legs of which have circular holes formed therethrough to snugly receive the axle 17, which may be inserted through the spaced 110

legs of the clips 21.

legs of these clips, as shown in Fig. 1. The clips 21 are bolted to the lower flat face of the brackets 13 by threaded bolts 22 provided with the nuts 23. By the means just described, it will be seen that the rear axle 17 may be strongly and rigidly secured to the rear portion of the toy vehicle, and in order to prevent this axle from working lengthwise through the legs of the clips 21, I preferably provide a second U-shaped clip 24 having axle receiving holes formed through the spaced legs thereof similar to the clips 21, but the legs of the clip 24 are sufficiently close together to permit the same 10 to be inserted between the legs of one of the clips 21, as shown in Fig. 2, and this clip 24 is preferably provided with a set screw 25 by means of which it may be rigidly clamped to the rear axle 17 to prevent the same from rotating and from shifting in a 20 lengthwise direction. In order that the front axle 18 may be pivotally secured to the forward portion of my toy vehicle, but one bracket 13 is rigidly secured to the forward portion of the body member 10, and to the lower face of this bracket is pivotally secured a clip 21' by means of a threaded bolt 22, and to prevent the front axle 18 from shifting in a lengthwise direction relatively 30 to the clip 21', I provide this axle with a clip 24' spaced between the legs of the clip 21' and secured to its axle by a set screw in the manner above described. In this manner it will be seen that very satisfactory 35 means is provided for pivotally securing the front axle 18 to the forward portion of the toy vehicle.

In order to provide convenient means for securing a draft tongue to the front axle 40 of my express wagon, I have provided the loop brackets 26 having a loop 26^a formed at one end thereof in order that the forward axle 18 may be inserted through this loop, and one of the brackets 26 is preferably 45 mounted upon the axle 18 upon each side of the forward clip 21', as will be apparent from Fig. 1. The forward end of the loop brackets 26 are preferably secured to a draft tongue 27 by means of angle plates 28. One 50 of these angle plates may be secured to each side of the tongue 27 by a bolt 29 which passes through the tongue and through one leg of each of the angle plates, while the opposite leg of each of these plates may be 55 secured to one of the brackets 26 by a bolt 30.

From the above description, when read in connection with the drawing, it will be apparent that I have provided a strong and 60 durable toy vehicle, in which the parts forming the running gear may be quickly assembled and taken apart, when desired, and it will also be apparent that due to the numerous bolt holes formed in the body member 10, the parts forming the running gear

of my toy vehicle may be assembled in various positions other than herein indicated, thereby permitting the child using this toy to exercise his ingenuity in assembling the parts of the same in various ways.

The construction parts herein disclosed, it will be understood, are so designed that they may be easily and quickly assembled to provide various different toy devices as explained in my copending application, Serial 75 No. 281,970, filed March 11, 1919.

I do not claim broadly herein features broadly claimed in my application Serial No. 292,877 above mentioned.

What I claim is:

1. In a construction toy, a body member provided with front and rear supporting axles, a perforated bracket, means for detachably securing the bracket to the under face of the body member, a front axle, a clip provided with downwardly bent legs having perforations therethrough to receive said axle, and means for pivotally securing said clip to the lower face of said bracket, and a locking clip secured to said axle between the legs of said pivoted clip.

2. In a construction toy, a body member perforated brackets secured to the under face of said body member adjacent the front and rear ends thereof, a front and rear axle respectively, U-shaped clips for rigidly but detachably securing the rear axle to the brackets positioned adjacent the rear end of said member, and a U-shaped clip for pivotally securing the front axle to the 100 bracket positioned adjacent the front end of said member.

3. In a construction toy, a body member provided with front and rear supporting axles, perforated brackets secured to the under face of said body member adjacent the front and rear ends thereof, a front and rear axle respectively, clips for rigidly but detachably securing the rear axle to the brackets positioned adjacent the rear end of said member, and a clip for pivotally securing the front axle to the bracket positioned adjacent the front end of said member, said front and rear brackets and clips being similar in construction and interchangeable.

4. A toy vehicle, comprising a body member, a bracket secured to the forward portion of said member to extend transversely thereof, a pair of brackets secured to the rear portion of said member to extend longitudinally thereof, an axle pivotally connected to said forward bracket, a rear axle connected to said rear brackets, and identical interchangeable means to connect the axles to each of said brackets.

5. A toy vehicle including a body member, a bracket secured to the under surface thereof, an axle, a clip pivotally connected to the bracket and having downwardly projecting legs perforated to receive the axle,

a locking clip secured to the axle and having spaced legs to engage the legs of the first clip and hold the latter against displacement.

5 6. A toy vehicle including a body member, a bracket secured thereto at the under side thereof, an axle, means pivotally securing said axle to said bracket, and a tongue having a pair of loop members attached thereto to engage the axle on opposite sides of the securing means and held against displacement thereby.

10 7. In a construction toy, a body member having a number of bolt holes formed therein, brackets upon the under face of said member adjacent the front and rear ends thereof, bolts extending through said holes for securing said brackets to said member in various positions, front and rear axles supporting said member, clips capable of being mounted in various positions upon said axles, and means for securing said clips to said brackets.

15 8. In a construction toy vehicle, a body member, front and rear axles operatively secured thereto, a draft tongue for said vehicle, and means for swingingly securing said tongue to one of said axles, comprising a loop bracket secured to said tongue in spaced relation thereto and having the loop of said bracket wrapped about said axle.

20 9. In a construction toy vehicle, a body member, a supporting axle pivotally secured thereto, a draft tongue, and means for swingingly securing said tongue to said axle, comprising a pair of loop brackets secured to said tongue in spaced relation thereto and having said axle extending through said loops.

25 10. In a construction toy vehicle, a body

member, a supporting axle pivotally secured thereto, a draft tongue, and means for operatively securing said tongue to said axle, comprising a pair of loop brackets having the loops thereof positioned around said axle, and angle plates for connecting said loop brackets to said tongue.

30 11. In a construction toy vehicle, a body member, a rear axle detachably but rigidly secured to said member, a front axle pivotally secured to said member, a draft tongue for said vehicle, and means for swingingly securing said tongue to said pivoted axle, comprising a loop bracket operatively secured to said tongue in spaced relation thereto and having the loop thereof positioned about said pivoted axle.

35 12. A toy vehicle having a body member, and front and rear supporting axles, means for connecting said body member to the front and rear axle comprising brackets secured to said body and clips attached to the axles, said clips and brackets being detachably connected, and means upon the axles separate from said clips to hold the axles against lateral movement relative to said body.

40 13. A toy vehicle having a body member, front and rear axles, means for connecting said body member to the front and rear axles, comprising brackets upon the body and clips upon the axles, means to detachably connect said brackets and clips, a draft tongue and means comprising a bracket having a loop in an end thereof to encircle the front axle to swingingly connect the tongue to the front axle.

In witness whereof, I have hereunto set my hand on the 10th day of July, 1919.

ALFRED C. GILBERT.
